 4 Claims. (Cl. 101—115)

This invention relates to means for fixing a driving roller for an automatic screen printing machine in the correct position in the intervals between successive advancements thereof by the intermittent driving means for the machine.

It is an object of the present invention to provide means for correctly fixing the driving roller of a screen printing machine in place in the intervals between the intermittent advancement thereof so that the printing on the cloth driven by means of the driving roller can be carried out accurately. This is accomplished by locking the driving roller in position when it stops, thus holding it in a fixed position and preventing the slight deviations from the regular stopping position which have heretofore been inevitable in such machines.

The invention is applicable to the usual type of screen printing machine for printing on a length of cloth, the machine having a driving roller positioned near one end thereof and an idler roller near the other end, and having an endless belt extending between these rollers. Driving means is connected to said driving roller to drive it intermittently. Along the upper run of the endless belt are a plurality of printing frames having printing squeegees, and means are provided for moving the screens into contact with the cloth on the belt when the belt is stopped. When the printing frames contact the cloth, the squeegees are moved back and forth across the screen to spread printing paste through the pattern on the screen and onto the cloth.

In order to hold the belt, and consequently the cloth carried thereby in the proper position when the belt has stopped moving, the present invention provides a gear on one end face of the driving roller. Adjacent the gear is a piston-cylinder mechanism having a member on the piston in the form of a rack which will fit into the teeth on the gear. The piston-cylinder mechanism can be connected to a source of pressure medium through an intermittently acting valve mechanism which is actuated in synchronism with the part of the printing machine which intermittently drives the belt. Thus when the belt is stopped, the piston-cylinder mechanism will be actuated so as to engage the rack with the gear and thereby fix the driving roller in position when it has stopped.

In the following description, this invention is more thoroughly explained with reference to the attached drawings in which,

FIG. 1 is a partial side elevation view of the automatic screen printing machine with a multiple printing squeegee moving mechanism of this invention;

FIG. 2 is a side-view of the remaining part of the said automatic screen printing machine, the figures to be joined at line T—T at the right end of FIG. 1 and line T—T at the left end of FIG. 2;

FIG. 3 is the plan view of FIG. 1;

FIG. 4 is the plan view of FIG. 2, FIGS. 3 and 4 to be joined at line U—U at the right end of FIG. 3 and line U—U at the left end of FIG. 4;

FIG. 5 is a schematic view of the device according to the invention for stopping the driving roller quickly at the desired position;

FIG. 6 is a sectional view, on an enlarged scale, of the rotary valve of FIG. 5 showing the valve in a working

2

position rotated about 45 degrees clockwise from the position shown in FIG. 5;

FIG. 7 is a cross-sectional plan view of a further embodiment of a rotary valve of the device of this invention;

FIG. 8 is a vertical sectional view of the rotary valve of FIG. 7;

FIG. 9 is a cross-sectional plan view of the rotary valve of FIG. 7 rotated from the position shown in FIG. 7;

FIG. 10 is the vertical sectional view of the rotary valve of FIG. 9.

FIG. 11 is a perspective view of the rotary valve shown in FIGS. 7 to 10; and

FIG. 12 is a perspective view of the rotary control member contained inside the said rotary valve.

As described above, this invention relates to a device for fixing the driving roller of an automatic screen printing machine in a correct position.

FIGS. 1 to 4 show the automatic screen printing machine equipped with this invention. Frame 1 extends the entire length of this machine, at one end of which is a driving roller 2 at the other end is a following roller 3. Between these rollers is stretched an endless belt 4 in such a way that the said belt 4 may be intermittently advanced in the direction shown by the arrow mark by intermittent revolutions of a driving roller 2. In this way, the following roller 3 is also revolved intermittently. On this endless belt 4, a plurality of printing frames 5 are arranged (FIGS. 2 and 4 show 10 printing frames) and all of them are held by main frame 6. Extending in the transverse direction of the said main frame 6 are several guide rails 7 (FIGS. 2 and 4 show 6 guide rails), on which squeegee holders 8 are placed so as to be movable reciprocally in the transverse direction of printing frames at the required time. These squeegee holders can be joined to each other throughout the full length of the frame, or occasionally a few of them can be mounted to move independently of the others. From these squeegee holders, two or more squeegees are hung in each printing frame so as to come in contact with screens which are stretched across the bottom of each printing frame. Color paste is stored between the said squeegees to print cloth through the screen 56 when the squeegee slides on the screens. At the entry end of the frame 1, the feeding device 9 for cloth 12 to be printed is installed so that the cloth 12 is continuously fed from the entry to the exit, being agglutinated on the endless belt in accordance with the advances of endless belt. At the exit of the frame, the dryer 10 is installed for the after-treatment of printed cloth as shown in FIGS. 1 and 3. The dryer 10 is equipped with a cloth discharge apparatus 11.

As seen in FIGS. 5 to 12, gear 17 is mounted on the side of driving roller 2 and piston 18 slidable in cylinder 20 is positioned adjacent to gear 17, the top of the said piston being machined to form a rack. A feed port and a discharge port for the compressed liquid are arranged at the upper and lower ends of cylinder 20, the said ports being coupled with the one ends of pipes 13 and 14. The other end of each pipe is connected with case 32 containing rotary valve 31.

The rotary valve contained in case 32 is designed in such a way that the said rotary valve may either rotate continuously, the said valve 31 being coupled directly with driving means which rotate continuously, or be made to perform a repetitive motion by arranging an intermittent motion generating means between the shaft of the rotary valve 31 and the continuously rotating driving means. A pipe 12 for feeding the compressed liquid to the rotary valve case 32 has one end connected with the said case and the other end with a trochoid pump, a sine-curve gear pump or other such small rotary pump 26 of large capacity and high pressure at the other end. On the pipe 12 running between rotary valve case 32 and

rotary pump 26, are positioned a receiver 24, a pressure gauge 25 and safety valve 23. Safety valve 23 is not necessarily required. The suction port of rotary pump 26 has connected thereto the suction pipe 30, and the outlet of safety valve 23 has connected thereto a discharge pipe 16, the free ends of suction pipe 30 and discharge pipe 15 extending into compressed liquid reservoir 28.

Rotary pump 26 and a motor 27 coupled thereto may be mounted directly on the housing for reservoir 28.

FIGS. 5 and 6 show the positions of driving roller 2, endless belt 4 and gear 17 at the moment at which these parts are at rest after they have been advanced one step by the driving mechanism for the printing machine (as shown in FIG. 4, this driving mechanism 33 is installed near the end of this printing machine for driving it), piston 18 is starting to rise and rotary valve 31 is rotating. While the printing machine is being operated, motor 27 and rotary pump 26 always rotate in a given direction at a constant velocity. Consequently, feed pipe 12 is filled with the compressed liquid, the said liquid being delivered through passage 31a in valve 31 and through pipe 13 to cylinder 20 as indicated by the arrow. The compressed liquid then enters the lower end of cylinder 20 so as to raise piston 18 in the direction shown by the arrow mark within a short period of time. This rise of the piston causes the rack 19 to engage the teeth of gear 17 mounted on the driving roller adjacent the said rack, thereby fixing driving roller 2 exactly at the correct position, and at the same time preventing the inevitable slight deviation of the stopping position of the said roller from the correct position.

Since the lifting power of piston 18 is in proportion to the ratio of sectional area of pipe 13 to the area of the bottom of piston 18, the said engagement may be carried out with great force. Accordingly, when the tension of endless belt is not uniform throughout its full length due to its uneven mounting on the circumferential surface of driving roller 2 or the teeth of gear 17 on driving roller 2 are slightly displaced from the position exactly opposite to rack 19 on piston 18, the tension of endless belt may be made uniform throughout its full length and the said teeth may be forced to the exact position for proper engagement mentioned above. In this way, the most exact feed pitch for endless belt 4 may be satisfactorily maintained.

During the time rack 19 on piston 18 rises, the liquid above the upper side of the piston inside cylinder 20 is forced through the port in the upper part of cylinder 20 through pipe 14 to rotary valve case 32, and is returned through the passages 31b in rotary valve 31 and through discharge pipe 15 to the compressed liquid reservoir 20 because of the position of the ports in rotary valve 31 which are turned to the proper position during the rising of piston 18. Consequently, the upward motion of piston 18 is performed as quickly as possible without any back pressure being generated in the liquid contained in the upper section of cylinder 20.

Furthermore, the dwell times of the piston at both ends of its upward stroke and downward stroke are sufficiently long that the printing may satisfactorily be carried out on endless belt 4 during the dwell time at the end of the upward stroke, and the endless belt may be fully advanced during the dwell time at the end of the downward stroke.

The dwell times described are about $\frac{1}{2}$ as long as the period for one complete cycle of advance and rest of endless belt 4.

During the dwell periods at the ends of the upward and downward strokes, rotary pump 26 continues to feed liquid. Accordingly, the feed liquid is temporarily accumulated in receiver 24, compressing the air in the upper part of the receiver. This prevents excess pressure from being exerted on piston 18 at the ends of the upward and downward strokes, because otherwise the cylinder might be damaged by the increase of the liquid pressure resulting from the constant feed of the liquid mentioned above.

Furthermore, safety valve 23 may be installed if desired for the purpose of furnishing a safety device to release the compressed liquid from the system through safety valve 23 and pipe 16 to compressed liquid reservoir 28.

After printing has been satisfactorily carried out on the endless belt 4 which has been stopped, the compressed liquid coming from feed pipe 12 is delivered in directions opposite to the arrow marks, namely, through pipe 14 to the inside of cylinder 20 above piston 18 when rotary valve 31 is moved to the position shown in FIG. 6. FIGS. 5 and 6 illustrate an embodiment in which rotary valve 31 performs an oscillating movement through an angle of 45°. FIG. 6 shows the rotary valve 31 turned 45 degrees to the right from the position in FIG. 5. The compressed liquid entering the section of the cylinder above the piston pushes the piston down, thereby disengaging rack 19 at the top of piston 18 from the teeth of gear 17. At the same time, the liquid beneath the piston 18 is returned through pipe 13, rotary valve 31 and discharge pipe 15 to the liquid reservoir 28.

The functions of receiver 24 and safety valve 23 during the period of time piston 18 is at the end of its downward stroke are quite similar to those at the end of its upward stroke as explained in the foregoing description.

At the time when rack 19 is disengaged from the teeth of gear 17, gear 17, driving roller 2 and endless belt 4 are advanced one step by other intermittent moving means of this printing machine.

FIGS. 7 to 10 show an embodiment where the rotary valve does not oscillate, but rather rotates continuously.

FIGS. 9 and 10 show the position of rotary valve 31 when it has been turned 180 degrees from the position shown in FIGS. 7 and 8. The rotary valve member is mounted on a shaft 29, and has a central web member 35 by which it is secured to the shaft. Extending in opposite directions from the web member and parallel to the shaft 29 are cylindrical walls 36a and 36b, each of which has a series of holes 37a and 37b therearound. These holes are in alignment with a single hole through the casing 32 which gives access to the conduit 15. In the casing 32 are passages 38 which open into the portion of the casing in which the cylindrical portion 36a is positioned, and with which an aperture 39a is aligned. The aperture 39a is aligned with the passage 38 which connects with the pipe 14 in the position shown in FIGS. 7 and 8, while in the position shown in FIGS. 9 and 10, it is aligned with the passage 38 communicating with pipe 13.

The holes 37b in the cylindrical portion 36b are alignable with a hole in the casing 32 which leads to the pipe 12. The cylindrical portion 36b also has an aperture 39b therein, which in one position is in alignment with the passage 41 in the valve casing which communicates with pipe 13, (as shown in FIGS. 7 and 8), and in the other position is in alignment with the passage 41 communicating with pipe 14 (as shown in FIGS. 9 and 10). The aperture 39b is positioned 180 degrees around the valve 31 from the aperture 39a.

It will be seen that, as the shaft 29 rotates to rotate the valve 31, the pipe 14 will first be connected to the pipe 15, while the pipe 12 will be connected to pipe 13, and when the valve has rotated 180 degrees, the pipe 12 will be connected to the pipe 14, and the pipe 13 will be connected to the pipe 15.

Moreover, the cover of rotary valve case 32 can be removed when the machine is stopped, and the timing of the rotary valve may easily be controlled by readjusting the position of the rotary valve by loosening the nut on the end of the rotary valve shaft.

Since in the device of this invention, the piston is actuated by liquid pressure, as explained above, satisfactory control of the driving roller, correction of its displacement and prevention of the error in feeding the belt may effectively be performed with the powerful pressure of the compressed liquid. Moreover, by arranging a receiver at an intermediate point in the pressure fluid system, the

capacity of the rotary pump may be kept at a minimum. Consequently, the electric power consumption can be minimized.

Furthermore, the small capacity of the rotary pump has the effect that the piston is operated smoothly without causing any percussion as a result of its vertical reciprocation, because the encounter of the valve ports with the feed and discharge ports at the times when the piston starts to move and stop during both the upward and downward strokes, is gradually accomplished.

It is thought that the invention and its advantages will be understood from the foregoing description and it is apparent that various changes may be made in the form, construction and arrangement of the parts without departing from the spirit and scope of the invention or sacrificing its material advantages, the forms hereinbefore described and illustrated in the drawings being merely preferred embodiments thereof.

What is claimed is:

1. In a screen printing machine, the combination of a driving roller for an endless belt on which the material to be printed is carried through the machine, means for intermittently driving said roller, and means for fixing said roller in position in the intervals between successive advancements thereof by said intermittent driving means, said fixing means comprising a gear on one end of the roller, a piston adjacent the gear having a rack on the end thereof toward the gear and engageable with the gear, a cylinder in which said piston is slidable, a reservoir for pressure fluid, a pump connected to said reservoir for

drawing pressure fluid therefrom, a rotary valve movable between at least two positions, and conduit means from opposite ends of said cylinder to said rotary valve and from said rotary valve to said pump and to said reservoir, 5 said rotary valve having a rotatable valve member having passages therein which in one position connect the conduit means from the pump to the conduit means to one end of said cylinder and connect the conduit means from the other end of said cylinder to the conduit means to 10 said reservoir, and which in the other position connect the conduit means from the pump to the conduit means to the other end of the cylinder, and connect the conduit means from the one end of said cylinder to the conduit means to said reservoir, whereby rotation of the rotary 15 valve causes said piston to reciprocate and causes the teeth of the rack to engage the teeth of the gear at timed intervals.

2. The combination as claimed in claim 1 in which said valve oscillates between two positions.

20 3. The combination as claimed in claim 1 in which said valve is continuously rotatable, and means for rotating said valve.

4. The combination as claimed in claim 1 in which said conduit means from the pump to the rotary valve 25 has a receiver connected thereto and a safety valve thereon, said safety valve having an overflow to said reservoir.
